UNITED STATES PATENT OFFICE.

JOHN EDWARDS BARBOUR, OF PATERSON, NEW JERSEY.

SMUDGING APPARATUS.

Application filed August 31, 1922. Serial No. 585,348.

To all whom it may concern:

Be it known that I, JOHN EDWARDS BARBOUR, a citizen of the United States, residing at Paterson, in the county of Passaic and 5 State of New Jersey, have invented certain new and useful Improvements in Smudging Apparatus, of which the following is a specification.

This invention relates to combustion apparatus and its principal object is to provide a combustion apparatus adapted especially for producing a smudge and in which saw-dust, in particular, may be burned and kept in continual combustion and afford 10 an ample smudge for as long as the apparatus is provided with fuel.

In the drawings,

Fig. 1 is a vertical sectional view of the apparatus;

20 Fig. 2 is a plan;

Fig. 3 is a sectional view on line 2—2, Fig. 1; and

Fig. 4 illustrates a detail.

In the example illustrated and specifically 25 described herein the apparatus is formed principally of sheet-iron.

a is a low cylindrical shell or wall which affords the base of the apparatus and may for that purpose have its lower edge wired, 30 as shown. It has a horizontal wall *b* secured thereto at a suitable elevation above said lower or wired edge. On this wall may be placed or secured, centrally thereof, an up- 35 standing element *c* whose basal part is preferably cylindrical and whose upper portion is conical; this element, as will appear, is not indispensable. Wall *b*, together with element *c* if present, affords a fuel support.

Upstanding from and suitably secured at 40 its base to the fuel support (specifically, to wall *b*) in surrounding and spaced relation to element *c* and within and spaced from wall *a* is an outer cylindrical shell *d*, which may have its upper edge wired. Into the 45 upper wired edge of shell *d* is removably fitted the outer down-turned edge portion *e*² of the horizontal flange or laterally projecting wall *e*' at the upper end of an inner cylindrical shell *e*, which is thus supported at its 50 upper end and projects down into shell *d* and is spaced all around therefrom, as at *f*. *g* designated handles on wall *e*' whereby the structure *e*—*e*'—*e*² may be lifted from the shell *d*. Shell *e* is open at top and bottom 55 and forms the fuel hopper. Shell *d* forms the draft flue *f*, and for the admission of the

draft it has openings *h* in its basal portion; the draft outlet is formed by openings *i* in wall *e*'. The draft inlet and outlet openings *h* and *i* are preferably arranged equidistantly around the central vertical axis of the apparatus. The hopper formed by shell *e* may be prolonged upwardly to increase its capacity by a cylindrical shell *j* which has an external bead *j*' near one end that is adapted on telescoping the shell *j* into shell *e* to abut the latter as a stop; when not in use shell *j* may be inverted and telescoped into shell *e* so as to be almost completely housed therein. 70

The basal portion of shell *d* is surrounded by a rotary sleeve damper *k* having ports *k*' to be moved into or out of registry with the draft inlet openings *h* to regulate the draft; *k*² is the handle of this damper. 75

l is a series of four angular ears arranged on shell *d* 90° apart and all projecting to the same level above the top of said shell so as to support a cooking vessel or the like *m* and leave an outlet for draft; two of these 80 may have the bail *n* of the apparatus pivoted thereto.

The openings *o* in the wall *a* allow free circulation of air under the wall *b*, so that the basal part of the apparatus cannot become so heated as possibly to burn the surface or set fire to any inflammable material on which it is placed. 85

The outlet afforded at the lower end of the hopper is spaced from and of less area 90 than the fuel support, over which it is arranged, in consequence of which saw-dust or other suitable comminuted fuel *A* placed in the hopper so as more or less to fill the same forms on the support in a pile *A'* 95 sloping (in the example shown, in all directions) from said outlet; thus the outlying portion of the pile underlies the flue *f*. Further; shell *d* being lateral of and close to the pile (in the example actually 100 supporting it laterally) the draft inlet means *h* stands lateral of and close to the pile. It is not easy to burn comminuted fuel, like saw-dust, slowly, so as to produce a smudge rather than a blaze, and also keep it 105 burning uninterruptedly. But I find it entirely possible with my apparatus to do this because, though the part of the fuel body which is undergoing burning is in the form of a pile or mass *A'*, the air is admitted directly to it, a good draft being afforded by the flue *f*, and as fast as the ma- 110

terial in the pile is consumed more falls from the hopper by gravity to take its place. In practice, the admission of air tends to form burnt-away vents in the pile, as indicated at A^2 in Fig. 1. Since the fuel burns in a pile or mass a profuse smoke or smudge is produced; the quantity of this can be regulated by manipulating the damper h . The wall d is made to support the pile laterally by so proportioning its diameter with reference to the spacing of the outlet of the hopper from the wall b (which represents the base of the pile) that the pile or pyramid A' cannot spread to the extent it 15 would otherwise assume. This makes it possible for the draft inlet openings h to be arranged so that the fuel pile will tend to cover them, whereby combustion proceeds effectively in the immediate vicinity of each inlet; this is an important factor in keeping the fuel burning uninterruptedly. The element c is not indispensable, as stated—without it a natural cone would be formed by the fuel itself down whose slope 20 the fuel to replenish that consumed would be precipitated; but it is found an advantage to provide element c , since the fall of the fuel takes place more readily down its smooth slope than it does down the slope 25 of such a natural cone.

From time to time the ashes which accumulate in the well formed at p may be dislodged therefrom through the draft inlet openings h into the exterior hearth well 30 g by taking the apparatus by the bail n and rolling it on its lower edge.

The apparatus may be utilized as a stove, for cooking and the like, by removing the structure $e-e'-e^2$, in which case of course 40 other fuel than saw-dust would be used.

Having thus fully described my invention, what I claim as new and desire to secure by Letters Patent is:—

1. A combustion apparatus including a fuel support, a fuel hopper having a downwardly opening outlet of less area than and arranged above and spaced from the support, whereby comminuted fuel placed in the hopper will form on the support in a pile sloping downwardly from the outlet, and an upstanding wall arranged lateral of and close to the base of the pile and forming with the latter a draft flue and having means to admit draft to the pile laterally thereof and above said means a draft outlet, said apparatus being otherwise closed to admission of draft to the pile.

2. A combustion apparatus including a fuel support, a fuel hopper having a downwardly opening outlet of less area than and arranged above and spaced from the support, whereby comminuted fuel placed in the hopper will form on the support in a pile sloping downwardly from the outlet, and an upstanding wall arranged around

and close to the base of the pile and also around the hopper and forming with the latter a draft flue and having means to admit draft to the pile laterally thereof and above said means a draft outlet, said apparatus being otherwise closed to admission of draft to the pile.

3. A combustion apparatus including a fuel support, a fuel hopper having a downwardly opening outlet of less area than and arranged above and spaced from the support, whereby comminuted fuel placed in the hopper will form on the support in a pile sloping downwardly from the outlet, and an upstanding wall arranged lateral of and close to the base of the pile and forming a draft flue lateral of the hopper and having means to admit draft to the pile laterally thereof and above said means a draft outlet, said apparatus being otherwise closed to admission of draft to the pile and the support having the part thereof under the hopper sloping downwardly toward said wall.

4. A combustion apparatus including a fuel support, a fuel hopper having a downwardly opening outlet of less area than and arranged above and spaced from the support, whereby comminuted fuel placed in the hopper will form on the support in a pile sloping downwardly from the outlet, and an upstanding wall arranged around and close to the base of the pile and also around the hopper and forming with the latter a draft flue and having means to admit draft to the pile laterally thereof and above said means a draft outlet, said apparatus being otherwise closed to admission of draft to the pile and the support having the part thereof under the hopper sloping downwardly all around toward said wall.

5. A combustion apparatus including a fuel support, a fuel hopper having a downwardly opening outlet of less area than and arranged above and spaced from the support, whereby comminuted fuel placed in the hopper will form on the support in a pile sloping downwardly from the outlet, and an upstanding wall arranged to support the base of the pile and forming a draft flue lateral of the hopper and having means to admit draft to the pile laterally thereof and above said means a draft outlet, said apparatus being otherwise closed to admission of draft to the pile.

6. A combustion apparatus including a fuel support, a fuel hopper having a downwardly opening outlet of less area than and arranged above and spaced from the support, whereby comminuted fuel placed in the hopper will form on the support in a pile sloping downwardly from the outlet, and an upstanding wall arranged around and to support the base of the pile and also around the hopper and forming with the latter a draft flue and having means to admit

draft to the pile laterally thereof and above said means a draft outlet, said apparatus being otherwise closed to admission of draft to the pile.

5 7. A combustion apparatus including a fuel support preventing admission of draft from below, and an upright structure arranged on said support and including an outer continuous wall and an inner continuous wall spaced from each other and forming between them a flue, said structure having draft inlet means in the outer wall near the support and draft outlet means in the upper part of the structure and the inner 10 wall forming a hopper for comminuted fuel and having at its lower end a fuel outlet spaced from and of less area than the support whereby fuel placed in the hopper will fall on the support and form in a pyramidal 15 pile.

20 8. A combustion apparatus including a fuel support preventing admission of draft from below, and an upright structure arranged on said support and including an outer continuous wall and an inner continuous wall spaced from each other and forming between them a flue, said structure having draft inlet means in the outer wall near the support and draft outlet means in the 25 upper part of the structure and the inner wall forming a hopper for comminuted fuel and having at its lower end a fuel outlet spaced from and of less area than the support whereby fuel placed in the hopper will 30 fall on the support and form in a pyramidal 35 pile and said outer wall having its diameter

so proportioned relatively to the spacing of said fuel outlet from the base of the pile that the pile will be supported laterally by the outer wall.

40 9. A combustion apparatus including a fuel support preventing admission of draft from below, and an upright structure arranged on said support and including an outer continuous wall and an inner continuous wall spaced from each other and forming between them a flue, said structure having draft inlet means in the outer wall near the support and draft outlet means in the upper part of the structure and the inner 45 wall forming a hopper for comminuted fuel and having at its lower end a fuel outlet spaced from and of less area than the support whereby fuel placed in the hopper will fall on the support and form in a pyramidal 50 pile and the part of said structure including the inner wall being removable from the remainder thereof.

55 10. A combustion apparatus including a horizontal wall affording a fuel support, an 60 upright continuous wall upstanding from the first wall and having a draft inlet means at its lower end and open at its upper end for escape of the products of combustion, and another continuous wall of less height 65 than the first continuous wall and upstanding from the horizontal wall and forming with the latter and around the first continuous wall a well open at the top.

70 In testimony whereof I affix my signature.

JOHN EDWARDS BARBOUR.
